CONNECTOR TRIM CAP FOR ROLL-UP AWNINGS

Donald MacLachlan, Riverside, Calif., assignor to Bridgeport Brass Company, Bridgeport, Conn., a corporation of Connecticut

Application November 24, 1958, Serial No. 53,499

Term of patent 14 years

(Cl. D21—6)

FIG. 1.

FIG. 4.

FIG. 2.

FIG. 5.

FIG. 3.

Figure 1 is a perspective view of a connector trim cap for roll-up awnings, showing my new design;

Figure 2 is a top plan view of the same;

Figure 3 is a side elevation;

Figure 4 is an end elevational view, as seen from the left of Figure 3; and

Figure 5 is an end elevational view, as seen from the right of Figure 3.

I claim:

The ornamental design for a connector trim cap for roll-up awnings, substantially as shown.
